UNITED STATES PATENT OFFICE.

LENTHEL S. DAVIS, OF WATERBURY, CONNECTICUT.

DESIGN FOR BUTTONS.

Specification forming part of Design No. 7,932, dated December 15, 1874; application filed April 8, 1874.
[Term of Patent 3½ years.]

To all whom it may concern:

Be it known that I, LENTHEL S. DAVIS, of Waterbury, in the county of New Haven and State of Connecticut, have invented a Design for Buttons, of which the following is a specification:

The nature of my design is fully represented in the accompanying drawings, to which reference is made.

A represents the center of the button, which is embossed with diamond-shaped facets. The

surrounding portions may be ornamented with any figures that may be selected.

What I claim as my invention is—

A design for a button, in which the center is embossed and covered with diamond-shaped facets, substantially as shown and described.

LENTHEL S. DAVIS.
